DIPPING MACHINE FOR PRODUCING SEAMLESS ARTICLES FROM SUBSTANCES IN SOLUTION

Albert Boehler, Berlin, Germany

Application October 26, 1933, Serial No. 695,357

5 Claims. (Cl. 18—24)

- The object of the invention is a dipping machine for producing seamless objects or articles from dissolved substances like rubber, cellulosic compounds and the like. In such machines cores corresponding to the shape of the objects to be produced are dipped into the solution either by lowering the cores into the solution contained in a stationary vat or by lifting a vat towards stationary cores or by moving the vat and the cores.
- 5 Thereafter by a return movement the cores are removed from the solution, a layer of which adheres to the core and forms the seamless article, which thereafter is removed from the core. In such machines for obtaining uniform products 10 it is important to maintain constant the depth of dipping, for which purpose it is necessary to maintain constant not only the length of the above dipping stroke but also the level of the liquid in the vat.
- 15 According to the invention this problem is solved by the feature that with the vat a container for the solution similar to a Mariotte bottle or chicken feed mechanism is firmly connected, from which container fresh solution flows into the vat for replenishing purposes only until a predetermined level, because in this level the exchange of air between the vat and the container is interrupted. The consequence thereof is that 20 at each dipping of the cores into the vat, provided an always uniform depth of dipping, the solution displaced by the cores always rises to the same level and that after each dipping, i. e., at the separation of the cores and the vat always 25 from the solution container so much solution flows into the vat as has adhered to the cores.
- 30 It can happen that the four bars of a core carrier are supporting cores with different displacement volumes, which cores are alternately dipped into the solution. Now because the different displacement volume causes a different raising of the 35 level of the solution in the different dipping operations it is impossible to adjust all the different dipping cores on the different supporting bars to the same limit of dipping level.
- 40 Now according to the present invention for enabling such a uniform adjustment the raising of the solution in the vat at the operation of dipping the cores into the solution is limited by an 45 overflow making independent of the displacement 50 volume of the dipping cores the maximum height of the level of the solution. Of course for that purpose the tank or container for the solution must have a surplus content corresponding to the maximal quantity of the solution flowing off into the overflow pipe.

The solution tank or container is firmly connected with the dipping vat and has at the top a filling opening, which may be closed in an air-tight manner by a lid or cover. The pipe connecting the tank with the vat is provided with a closure valve, which is closed, if the solution container is refilled, and which then remains closed until the filling opening is again sealed in an air-tight manner.

In the drawing such a dipping machine is 10 shown diagrammatically.

Fig. 1 is a sectional elevation of the dipping machine.

Fig. 2 is a similar partial view of a modification.

The core-carrier 1 supports four core supporting bars, 2a, 2b, 2c, 2d, the cores 3a, 3b, 3c, 3d of which are to be dipped alternately into the solution. The carrier 1 is rotatable about an axle 4, which can be lowered together with the carrier 1 into the position 1' indicated in dotted lines, in which position the downwardly suspended cores as for instance 3a are embedded into the solution in the dipping vat 5. Any suitable means may be used for lowering the carrier, the means 15 shown comprising a rope 15 formed in a loose loop around the axle 4, and passing over a pulley 17 to a source of power not shown. The vat 5 is filled with solution to the level 6, in which 20 level to the vat is connected a tank or container 7 supported by a bracket 8 secured to the vat. Liquid from the tank 7 may enter into the vat 5 through the pipe 9 provided with a closure valve 25 10. The tank 7 is arranged above the vat 5 and has at the top a filling opening 11 with a cover 30 12 for closing the opening 11 in an air-tight manner. At the same level, at which the connecting pipe 9 is connected to the vat 5 or at a slightly 35 higher level an overflow pipe 13 can be provided, from which under certain conditions solution may 40 flow into a return conduit 14. Instead of moving vertically the core-carrier 1 for the purpose of dipping the vat 5 can be moved vertically together with tank 7 or the carrier as well as the vat can both be moved vertically.

According to the modification shown in Fig. 2 to the connecting pipe 9 is connected a swingable pipe 9a projecting into the vat 5. By vertical swinging adjustment of this pipe 9a the level, until which after the return part of the dipping 50 stroke the solution is delivered from the tank 7 to the vat, can be regulated at will. In a similar manner the overflow pipe—if any—can be constructed in the form of a vertically swingable pipe 13a, by the adjustment of which the raising 55

of the level of the solution in the vat can be adjusted at will in the dipping operation.

By means of these adjustable inlets and outlets the maximum and minimum levels can be regulated to closely approximate the minimum displacement of the cores and the amount of fluid passing through the overflow pipe reduced to a minimum. Also the adjustable overflow affords a convenient means of closely regulating the depth 10 of submergence of the cores.

The operation of the device is as follows:

At the beginning of work the vat 5 is filled with the solution nearly to the level 6. The closure valve 10 is closed and thereupon the cover 12 is 15 opened and through the opening 11 also the tank or container 7 is filled with solution. Thereupon the cover 12 is closed in an air-tight manner and the valve 10 is opened. Now with exchange of air through the pipe 9 the solution in the vat 5 20 rises until the level 6, at which the exchange of air is interrupted and thereby also the outflow of solution from the tank 7 into the vat 5. If now for instance by lowering the core-carrier 1 a series of cores as for instance 3a is dipped into the 25 solution in the vat 5, the cores are displacing a certain volume of solution, whereby the level in the vat 5 is raised. Because by the same cores 3a in repeated dipping operation always the same amount of solution is displaced, the level of the 30 solution at each dipping operation rises to the same height, whereby a dipping of the cores 3a into the solution to always the same depth is secured. At the return part of the dipping stroke the level of the solution in the vat 5 falls somewhat beneath the initial height, because some solution adheres to the cores. However now the 35 exchange of air between the vat 5 and the tank 7 becomes effective, whereby it is caused that the vat 5 is refilled from the tank 7 precisely to the level 6. This operation is repeated until the desired number of articles has been produced by the cores 3a.

In the event that the cores as for instance 3b and 3c supported by the different bars as for instance 2b and 2c may have different volumes the vat 5 can still be provided with an overflow pipe 13, the level of which is selected so with respect to the level of the lower orifice of the tube 9, that in the operation of dipping the cores of 50 smallest displacement volume the solution in the vat 5 rises at least until the overflow pipe 13. If cores of a bigger displacement volume as for instance 3c are dipped, more solution is displaced; however the level of the solution in the vat 5 55 dipping cannot rise above the overflow pipe 13, because the excess or surplus of the displaced solution flows through the overflow pipe 13 into the return pipe 14. Thereby it has been made possible to adjust to the same dipping depth the cores of the different bars independently of any differences in displacement volume, because independently of the displacement volume the rising of the level of the solution in the vat 5 at the dipping operation is always the same.

Of course it is to be understood that I do not limit myself to any details above described.

Now what I claim is:—

1. In a dipping apparatus, a dipping tank to contain moldable material in fluid condition, a conveying means, a plurality of mold cores supported thereon, means to operate said conveying means to submerge said cores to a substantially uniform, predetermined depth in said material, means for controlling the level of said material irrespective of the displacement thereof by said cores, said means comprising a source of supply to maintain a minimum level and means for removing a portion of said material upon increase of the same beyond a predetermined maximum level the volumetric difference between said maximum and minimum levels being substantially equal to the displacement of the cores.

2. An apparatus for forming articles on cores by dipping said cores in moldable material in fluid condition, comprising in combination a tank for containing said material, a conveyor means, a plurality of mold cores supported thereon, means to operate said conveyor means, to alternately submerge said cores in said material and to remove them therefrom, means for maintaining a predetermined maximum level of said material in said tank relative to said cores when the same are submerged and means of maintaining a predetermined minimum level of said material in said tank when said cores are removed therefrom, said maximum and minimum levels delimiting a volume of said material substantially approximating the displacement of said cores.

3. An apparatus for forming articles on cores by dipping said cores in moldable material in fluid condition, comprising in combination a tank for containing said material, a conveyor means, a plurality of mold cores mounted upon said conveyor means, means to operate said conveyor means to alternately submerge said cores in said material and to remove them therefrom, and means for limiting the maximum and minimum levels of said material in said tank to provide a difference of volume between said levels substantially approximating the volume of said material displaced by said cores.

4. The method of forming articles upon mold cores which comprises the steps of moving the cores into a tank, containing moldable material in fluid condition, a predetermined distance relative to the tank and controlling the maximum and minimum levels of the said material, in said tank, to delimit a volume approximating the displacement of said cores.

5. The method of forming articles upon mold cores which comprises the steps of mounting the cores upon a carrier and moving the carrier with the cores thereon into predetermined core dipping relation to a tank containing moldable material in fluid condition so as to dip said cores in said material and maintaining maximum and minimum levels of the material in said tank to delimit a volume which approximates the displacement of said cores whereby said cores are immersed in said material to a uniform depth notwithstanding voluminal variations in said cores.

ALBERT BOECLER.
